UNITED STATES PATENT OFFICE.

STANISLAW WADAS, OF PHILADELPHIA, PENNSYLVANIA.

MECHANICAL-STOKER FURNACE GRATE.

Application filed September 15, 1921. Serial No. 500,751.

To all whom it may concern:

Be it known that I, STANISLAW WADAS, a citizen of the United States of America, residing at Philadelphia, in the county of 5 Philadelphia and State of Pennsylvania, have invented certain new and useful Improvements in Mechanical-Stoker Furnace Grates, of which the following is a specification.

10 This invention relates to certain new and useful improvements in mechanical stoker furnace grates and its object is to provide a simple and durable apparatus which will secure a more perfect and uniform combustion of fuel than has heretofore been attained, and consequently a more economical and efficient operation for obtaining greater 15 and more uniform steam pressure.

With the above general object in view and 20 others that will appear as the nature of the invention is better understood, the same consists in the novel form combination and arrangement of parts hereinafter more fully described, shown in the accompanying drawings and claimed.

25 In the drawings forming a part of this specification and in which like characters of reference indicate corresponding parts throughout the several views,

30 Figure 1 is a side elevational view of a mechanical stoker grate constructed in accordance with the present invention shown operatively associated with certain accessories which are illustrated in vertical section,

35 Figure 2 is a front elevational view of the stoker grate shown in Figure 1.

Figure 3 is a top plan view of the device shown in Figure 2,

40 Figure 4 is a fragmentary view showing the lower portion of the device shown in Figure 2 in substantially central longitudinal section,

45 Figure 5 is a view similar to Figure 4 of the upper portion of the device shown in Figure 2,

Figure 6 is a side elevational view of one of the grate bars of one set forming part of the main grate, and

50 Figure 7 is a view similar to Figure 6 of one of the grate bars of the other set of the main grate.

The furnace is constructed with a fire bridge 5 and an arch 6, above which is 55 placed the boiler 7. Between the front of

the furnace and the fire bridge are placed three grates, the forward and upper one of which 8 is the coking grate, the intermediate or second one of which 9 is the main inclined grate, and the third or lower and inner one of which 10 is the dumping grate. The main grate 9 is composed of two series of grate bars one of which is vibratory about a transverse pivot near the lower end of 60 said main grate while the other of which is vibratory about a transverse horizontal pivot near the upper end of said main grate, a grate bar of the first series being shown in Figure 6 and that of the second series being shown in Figure 7 and respectively 65 designated by the numerals 11 and 12.

The present stoker includes a pair of side frames 13 which are connected intermediate their ends by a transverse horizontal bar 14 upon which the grate bars 11 and 12 rest 70 at their central portions, said grate bars being cut out to form hook-shaped members 15 and 16 disposed to loosely partially embrace the bar 14 so as to permit transverse vibration of said bars while retaining the 75

same against downward longitudinal movement as they would otherwise tend to move by gravity by reason of the fact that they are arranged at an inclination. Further 80 transverse bars 17 and 18 connect the frames 13 at a point beneath the upper and lower ends of the grate bars 11 and 12 and furnish further rests or supports for said grate bars at times during their operation. The grate bars 11 are provided with eyes 19 near their 85

lower ends through which a transverse pivot rod 20 extends, while the grate bars 12 are provided with transverse openings 21 near their upper ends through which a substantially horizontal transverse pivot rod 22 extends, the grate bars 11 being cut out as at 90 23 so that the pivot rod 22 does not extend therethrough but is disposed beneath the same in said cut out. A pair of rock shafts 24 and 25 are journaled in the top inclined members of the frames 13 respectively near the upper and lower ends of the latter, and these rock shafts are provided with relatively long crank portions 26 and 27. The 95

crank portions 26 engage in forwardly directed hook members 28 formed on the upper ends of the grate bars 11 and the crank portion 27 engages somewhat similar hook members 29 provided on the lower portion of the grate bars 12, said crank portion 26 passing 100 105 110

under the upper ends of the bars 12 and the crank portion 27 passing under the lower ends of the bars 11.

An arm 30 is rigid with and depends from a member of the rock shaft 24 and is connected by a link bar 31 to the free end of an angular member 32 which has its other end pivoted as at 33 on a plate 34 which is firmly fixed upon the front plate 10 of the furnace. The angular member 32 is loosely and pivotally connected as at 35 between the pivot 33 and the connection of the link 31 with said member 32 with a sleeve 36 which is adjustably fixed upon a depending bar 37 strapped to an eccentric 38 which is fastened upon a transverse horizontal shaft 39. The shaft 39 is suitably journaled in the frames 13 beneath and forwardly of a hopper 40 provided at the upper portion of the apparatus outwardly of the arch 6, and on said shaft 39 is also fixed another eccentric to which is strapped a further but longer depending bar 41 which in turn carries an adjustable sleeve 42 which is loosely and pivotally connected as at 43 to the central portion of an angular member 44, the member 44 having one end pivotally attached to the plate 34 as at 45 and having its other end pivoted to one end 30 of a link bar 46. The link bar 46 has its rear end pivoted to a depending arm 47 fixed to a member of the rock shaft 25.

A still further eccentric is provided upon the shaft 39 near one end thereof outwardly 35 of the eccentric 38, and an upwardly extending slotted bar 48 is strapped to this further eccentric, the bar 48 having a longitudinal screw 49 and a nut 50 adjustable thereon within the slot of the bar longitudinally of the latter, which nut is pivotally connected as at 51 to the ends of upwardly extending arms 52 which are rigid with a horizontal rocking feed bar 53. The feed bar 53 substantially forms the bottom of the hopper 40 and includes a substantially flat plate portion beneath which is disposed a rigid horizontal bar 54 over which the forward upper ends of the bars 55 of the coking grate 8 are hooked, said coking grate bars 55 being extended rearwardly through a slot in the plate 34 and having their lower rear ends resting upon the upper ends of the grate bars 11. In order to provide for the engagement of the grate bars 55 only 55 with the grate bars 11 and to provide spaces between the contacting ends of the grate bars 11 and 55 for the admission of air, the grate bars 55 are provided with longitudinal narrow ribs 56 upon their under sides which 60 rest upon the upper ends of the grate bars 11.

A substantially horizontal ash pit 57 with downwardly converging sides is provided beneath the grates 8, 9, and 10, and above 65 the rear portion of this ash pit are disposed

a plurality of transverse rotatable grate bars 58 forming the dumping grate 10, said grate bars being preferably journaled in the frames 13 slightly below and rearwardly of the lower ends of the main grate bars 70 and being intergeared by means of spur gears 59 or the like whereby rotation of one bar will cause the opposite rotation of the adjacent bar for dumping the ashes into the ash pit as the same is formed by consumption of the coal upon said grate bars 58. A spiral conveyor 60 is journaled longitudinally and centrally of the ash pit 57 and so disposed as to convey the ashes forwardly from a point beneath the grate bars 58 so as to keep the ash pit clean or substantially so and this conveyor is also longitudinally slideable or displaceable for a purpose which will presently become apparent. A transverse horizontal shaft 61 is journaled in the frames 13 beneath the shaft 39 and has a relatively large bevel gear 62 fixed thereon in position to mesh with a bevel pinion 63 fixed upon the forward end of the shaft of the conveyor 60 which projects through the plate 34, the gear pinion 63 being normally held in engagement with the bevel gear 62 by means of a relatively strong helical spring 64 which surrounds the shaft of the conveyor 60 between the plate 34 and the pinion 63, said spring 64 acting to displace the conveyor to the full line position of Figure 4 from the dotted line position thereof. The means for rotating the shaft 39 is not illustrated but said shaft may be rotated by a gearing or by pulley or by a small engine with the rotation thereof timed, and in order to transmit such rotation of the shaft 39 to the shaft 61, aligned sprocket wheels 65 and 66 are respectively secured upon adjacent projecting ends of the shafts 39 and 61 with an endless sprocket chain 67 passing therearound. In order to throw the conveyor 60 out of operation and to maintain the same out of operation, the shaft of said conveyor 60 is associated with a hand lever 68 having a spring pressed catch and rack bar whereby rearwardly tilting of the lever 68 will bring the latch into engagement with a tooth of said rack bar as shown by dotted lines in Figure 4 for holding the conveyor 60 in a rearward position with the pinion 63 out of engagement with the gear 62.

Another sprocket wheel 69 is fastened upon the projecting end of the shaft 61 in line with a sprocket wheel 70 fastened upon the projecting end of the shaft of one of the grate bars 58, and an endless sprocket chain 71 passes around the sprocket wheels 69 and 70 so as to transmit motion from the shaft 61 to the grate bars 58 in the presence of the gears 59. The shaft of the grate bar which carries the sprocket wheel 70 is denoted by the numeral 72 and as shown in

Figures 1 and 3, said shaft is provided with clutch teeth arranged to cooperate with clutch teeth upon the adjacent side of the hub 73 of the sprocket wheel 70, which hub 5 is slidably mounted upon the reduced free end portion of the shaft 72 so as to provide for ready disengagement of these clutch teeth whereby rotation may or may not be imparted to the grate bars 58 as desired. A 10 suitable lever 74 is associated with the hub 73 so that the latter may be readily slid for engaging or disengaging said clutch teeth while a hook 75 may be disposed to engage the lever 74 to insure retention of the clutch 15 teeth for engagement against accidental disengagement thereof while at the same time permitting manual disengagement of said clutch teeth.

In operation, coal is delivered in any desired manner into the hopper 40 and the teeth of the hub 73 are normally disengaged as is also the bevel pinion 63 and the shaft 39 is then slowly rotated, the feeding device 53 being rocked so as to project and retract 25 and gradually feed the coal onto the coking grate 8 which is slowly agitated by this connection with the feeding device and its association with the upper ends of the grate bars 11. At the same time, the shafts 24 30 and 25 are slowly rocked so as to cause vertical swinging to the grate bars 11 and 12 about their respective pivot rods 20 and 22 so that each grate bar 11 vibrates one of the grate bars 55. The fuel is thus gradually 35 removed from the hopper 40 down over the surface of the coking grate and the main grate until it reaches and covers the dumping grate, reaching to the front of the fire bridge 5. As the fuel passes upon the coking 40 grate and becomes ignited, it receives a sufficient quantity of air through the spaces between the adjacent ends of the grate bars 55, 11 and 12. The smoke generated in the coking process is thus quickly and practically 45 entirely consumed, adding to the heat of the furnace and substantially obviating its escape through the stack. Through the agitation of the coking and main grates, the fuel is gradually passed down upon the main 50 grate, where it continues to receive a quantity of air duly proportioned to the state of its combustion. By the time the fuel reaches the lower portion of the main grate 9, it is effectively coked and live fuel is in little or 55 no danger of falling through the spaces between the grate bars into the ash pit below.

As the ashes accumulate upon the grate bars 58 of the dumping grate 10, they may be dumped into the ash pit 57 from time to 60 time by throwing the hub 73 into operation by means of the lever 74 so that the grate bars 58 are rotated. Also, said ashes may be conveyed out of the ash pit from time to time so as to insure proper updraft between 65 the grate bars 58 by permitting the forward

movement of the conveyor until the pinion 63 engages the gear 62.

From the foregoing description, it is believed that the construction and operation as well as the advantages of the present invention will be readily understood and appreciated by those skilled in the art. 70

Minor changes may be made without departing from the spirit and scope of the invention as herein claimed. 75

What is claimed as new is:

1. In a mechanical stoker furnace grate, a hopper, a rocking feeder bar journaled upon a horizontal axis, a coking grate including separate grate bars having their upper ends pivoted to said feeder bar and cooperating therewith to form a bottom for said hopper, a main grate including grate bars alternate ones of which are mounted near their lower ends for swinging movement or vibration and the remaining ones of which are mounted near their upper ends for swinging vibration, said grate bars of the coking grate having their lower ends resting upon the upper ends of said alternate 80 grate bars of the main grate, the bars of the coking and main grate extending longitudinally of the furnace with the bars of the main grate inclined, and means to vibrate all of the grate bars of said main grate. 85

2. In a mechanical stoker furnace grate, a hopper, a rocking feeder bar journaled upon a horizontal axis, a coking grate including separate grate bars having their upper ends mounted on said feeder bar, and cooperating therewith to form a bottom for said hopper, a main grate including grate bars alternate ones of which are mounted near their lower ends for swinging movement or vibration and the remaining ones of which are mounted near their upper ends for swinging vibration, said grate bars of the coking grate having their lower ends resting upon the upper ends of said alternate 90 grate bars of the main grate, the bars of the coking and main grate extending longitudinally of the furnace with the bars of the main grate inclined, means to vibrate all of the grate bars of said main grate, 95 and a transverse driving shaft, the means for vibrating the grate bars of the main grate and the means for rocking said feeder bar being operatively connected to said shaft. 100

3. In a mechanical stoker furnace grate, a hopper, a rocking feeder bar journaled upon a horizontal axis, a coking grate including separate grate bars having their upper ends mounted on said feeder bar and cooperating therewith to form a bottom for said hopper, a main grate including grate bars alternate ones of which are mounted near their lower ends for swinging movement or vibration and the remaining ones of which are mounted near their upper ends for vibration, said 110 grate bars of the coking grate having their 115

lower ends resting upon the upper ends of said alternate grate bars of the main grate, means to vibrate all of the grate bars of said main grate, the bars of the coking and main 5 grate extending longitudinally of the furnace with the bars of the main grate inclined, the means rocking the bars of the main grate including transverse rock shafts having upwardly directed crank portions, 10 and said grate bars including hook members engaging said crank portions.

4. In a mechanical stoker furnace grate, a hopper, a rocking feeder bar journaled upon a horizontal axis, a coking grate including 15 separate grate bars having their upper ends mounted on said feeder bar, and cooperating therewith to form a bottom for said hopper, a main grate including grate bars alternate ones of which are mounted near their lower 20 ends for swinging movement or vibration and the remaining ones of which are mounted near their upper ends for vibration, said grate bars of the coking grate having their lower ends resting upon the upper ends of 25 said alternate grate bars of the main grate, means to vibrate all of the grate bars of said main grate, the means rocking the bars of the main grate including transverse rock shafts having upwardly directed crank portions, 30 and said grate bars including hook members engaging said crank portions, a pair of frames in which said rock shafts are journaled, a transverse bar connecting said frames at a point substantially midway between the ends of the grate bars of the main 35

grate, and hook members upon the grate bars of the main grate engaging said transverse bar to hold said grate bars of the main grate against downward displacement, the last named grate bars being rearwardly inclined, and the bars of the coking and main 40 grate extending longitudinally of the furnace.

5. In a mechanical stoker furnace grate, a hopper, a rocking feed bar having a transverse rigid bar member, a coking grate including a plurality of grate bars with hooks upon the forward ends of the same engaging over said rigid bar member and cooperating with said rocking feed bar to form a bottom for said hopper, a main grate including bars upon the upper ends of which the lower ends of the coking grate bars rest, said coking grate bars being provided with longitudinal narrow ribs spacing the lower ends of said coking grate bars from the upper ends of the main grate bars for the admission of air, said main grate including grate bars alternate ones of which are mounted near their lower ends for swinging vibration, said 55 grate bars of the coking grate being of such width and with their longitudinal ribs so disposed as to only engage said alternate ones of the main grate bars, the bars of the coking and main grate extending longitudinally of the furnace with the bars of the main grate inclined.

In testimony whereof I affix my signature.

STANISLAW WADAS.
